US0D1021343S

(12) **United States Design Patent** (10) **Patent No.:** **US D1,021,343 S**
(45) **Date of Patent:** **** Apr. 9, 2024**

(54) **FOOTWEAR**

- (71) Applicant: **adidas AG**, Herzogenaurach (DE)
(72) Inventor: **Mark Miner**, Los Angeles, CA (US)
(73) Assignee: **adidas AG**, Herzogenaurach (DE)

(**) Term: **15 Years**

(21) Appl. No.: **29/854,545**

(22) Filed: **Sep. 26, 2022**

Related U.S. Application Data

(63) Continuation of application No. 29/716,812, filed on Dec. 12, 2019, now Pat. No. Des. 968,059.

(30) **Foreign Application Priority Data**

Jun. 12, 2019 (EM) 006570859

(51) **LOC (14) Cl.** **02-04**

(52) **U.S. Cl.**

USPC **D2/969**

(58) **Field of Classification Search**

(74) *Attorney, Agent, or Firm* — Kilpatrick Townsend & Stockton LLP

(57) **CLAIM**

The ornamental design for footwear, as shown and described.

DESCRIPTION

FIG. 1 is a lateral side view of footwear, showing my new design.

FIG. 2 is a medial side view thereof.

FIG. 3 is a front view thereof.

FIG. 4 is a back view thereof.

FIG. 5 is a top view thereof.

FIG. 6 is a bottom view thereof.

FIG. 7 is a back perspective view thereof.

FIG. 8 is another back perspective view thereof; and,

FIG. 9 is a front perspective view thereof.

The portions of the footwear surrounded by dashed lines illustrate portions of the footwear that form no part of the claimed design.

1 Claim, 9 Drawing Sheets

US D1,021,343 S
